FIG. 13

FIG. 14

FIG. 1 is a perspective view of a combined rotatable sign tower and booth showing our new design;

FIG. 2 is a top plan view of the same;

FIG. 3 is a side elevational view of the same;

FIG. 4 is another side elevational view taken 90° from the position of FIG. 3;

FIG. 5 is a transverse sectional view taken in the plane indicated by the line 5—5 of FIG. 4;

FIG. 6 is a perspective view of a modified form of the design shown in FIG. 1;

FIG. 7 is a top plan view of the same;

FIG. 8 is a side elevational view of the same;

FIG. 9 is another side elevational view taken 90° from the position of FIG. 8;

FIG. 10 is a transverse sectional view taken in the plane indicated by the line 10—10 of FIG. 9;

FIG. 11 is a perspective view of still another modified form of the design shown in FIG. 1;

FIG. 12 is a top plan view of the same;

FIG. 13 is a side elevational view of the same;

FIG. 14 is another side elevational view taken 90° from the position of FIG. 13;

FIG. 15 is a transverse sectional view of the same taken in the plane indicated by the line 15—15 of FIG. 14.

The dominant features of our design reside in the portions shown in full lines.

This is a continuation of design applications Ser. Nos. D-147, D-148 and D-149, all filed Dec. 6, 1965, now abandoned.

We claim:

The ornamental design for a combined rotatable sign tower and booth, as shown and described.
